UNITED STATES PATENT OFFICE

BRAUDDUS BROCK FORTNEY, OF LOUISVILLE, KENTUCKY, ASSIGNOR, BY DIRECT AND
MESNE ASSIGNMENTS, TO AMERICAN SAFETY HEADLIGHT CORPORATION, A COR-
PORATION OF DELAWARE

HEADLIGHT

Application filed March 12, 1928. Serial No. 261,004.

My invention relates to headlights for vehicles and particularly to the type designed to eliminate the glare usually imposed upon the drivers of vehicles or pedestrians moving against the light.

It is my purpose to so construct a headlight of this character that a relatively powerful light can be employed without imposing any glare whatever upon the driver of an approaching vehicle; and which will project all the light energy, emanating from the light source, upon the road in advance of the vehicle equipped with my improved light.

I will describe my invention in the best form known to me at present, but it will be apparent that same is susceptible to change in form and proportion, and to desirable additions with the exercise of only ordinary mechanical skill.

With the foregoing and other purposes in view my invention embodies the details of construction and the arrangement and combination of parts to be hereinafter more fully described and particularly claimed.

In describing my invention in detail reference will be had to the accompanying drawing wherein like characters of reference denote corresponding parts in the several views, and in which

Figure 1 is a vertical section through my improved headlight;

Figure 2, a front elevation of my headlight; and

Figure 3, a side elevation of the forward end of an automobile equipped with my improved headlight and showing the manner in which the light rays are projected upon the road.

With particular reference to the drawing my improved headlight is shown as comprising a body 10, in which is telescoped a reflector 11. The reflector 11 carries at its rear end a source of light in the form of an electric bulb 12. Mounted in the reflector 11 adjacent its forward end is a short focal double convex condensing lens 13. The forward end of body 10 is closed except for an opening 15 having its center in the vertical axis of said forward end, but below the horizontal axis 50 of said end.

Mounted in the body 10 is a partition 16 having a concentrically disposed circular opening 17 of less diameter than the opening 15.

Connecting the openings 15 and 17 is a road projector casing in the form of a conical conduit 18 closed at its forward end by a transparent window 19.

Convex condensing lens 13, condenses all of light from source 12 and reflector 11, and converges it within the opening 17, at which point all of the light energy is diverged into road projecting casing 18 and upon the road through window 19. The opening 17 is termed the "focal window" because it is substantially at the point at which the condensing lens condenses all of the light as described and would be substantially coincident with the focal point of said lens.

It is apparent that owing to the relative positions of the openings 17 and 15 the casing 18 will be inclined downwardly in a forward direction and will accordingly cause the diverging light energy to be projected upon the road, the upward diverging rays of light 75 being reflected downward by the casing 18 causing the full light energy from the source and reflector to strike the road as shown in Fig. 1, with an obvious absence of glare regardless of the volume of the light energy.

The light beam is converged along the beam lines shown in the drawing, whereupon convergence at the focal point, the beam will be inverted in a divergent beam the outlines of which is shown in Figure 3. The unreflected portion of the beam diverges below the optical axis at the same rate as the projector casing or conduit below the optical axis, that is, it is parallel to the lowest surface.

Furthermore by employing the double convex condensing lens 13 and converging all of the light energy within the small aperture 17, I am enabled to utilize all of the light energy from the source and the reflector for projection upon the roadway and at the same time to eliminate all glare of light produced.

It is well known that the general type of headlight now in use produces an intense glare from the source of light and the reflecting points. In my invention it is obvious

that the glare is prevented by the process of converging all of the light rays at a small aperture within the body of the headlight and projecting them upon the road from that source.

5 I claim:—

1. A headlight comprising a body, a reflector within the body, a source of light located at the focus of said reflector, a lens co-operating with said reflector to converge the rays of light within the body of the headlight, a substantially conical conduit disposed within said body with the smaller end thereof adjacent the converging point of the rays, the larger end of said conical conduit being eccentrically disposed below the optical axis of the projecting system, and including interiorly of the upper interior surface a mirrored reflective surface, said reflective surface being disposed in the path of the rays above the optical axis.
- 10 2. In a headlight, the combination which includes a reflector and lens within the body of the headlight arranged to converge the light from a source to a focal area within the headlight, a conically formed secondary reflector conduit having its small end concentric with the optical axis of said reflector and lens combination, and positioned adjacent the focal area of said light, and having its forward end eccentrically disposed with the optical axis to extend below the same, said conduit having a reflecting surface at its upper interior portion.
- 15 3. In a headlight, the combination which includes a source of light and a reflecting and condensing system arranged to converge the light from a source to a focal area within the headlight, a conically formed secondary reflector conduit having its small end substantially concentric with the optical axis of said reflecting and condensing system adjacent the focal area of said light, and its forward end eccentrically disposed with the optical axis to extend below the same, said conduit having a reflective surface at its interior portion to direct the light rays inverted above the optical axis to below the same.
- 20 4. In a headlight, the combination which includes a source of light and a condensing system arranged to converge the light from said source to a focal area within the headlight, a conically formed reflector conduit having its small end concentric with the optical axis of said condensing system adjacent the focal area of said light, and having its forward end eccentrically disposed with the optical axis to extend below the same, said conduit having a reflecting surface at its upper interior portion.

In testimony whereof I hereunto affix my signature.

BRAUDDUS BROCK FORTNEY.
